RADIO RECEIVER CABINET

Melvin H. Boldt, 933 N. Glenayre Drive, Glenview, Ill.
60025, and Tom Takeuchi, 1242 W. Grace St., Chicago,
Ill. 60622

Filed May 27, 1969, Ser. No. 17,375

Term of patent 14 years

Int. Cl. D14—03

U.S. Cl. D56—4

FIG. 1

FIG. 2

FIG. 3

FIG. 1 is a front perspective view showing the top, front and side of our design for a radio receiver cabinet;

FIG. 2 is a front elevational view, the rear being substantially a mirror image thereof; and

FIG. 3 is a side elevational view, the opposite side being substantially a mirror image thereof.

We claim:

The ornamental design for a radio receiver cabinet, substantially as shown and described.
